UNITED STATES PATENT OFFICE.

JOHN GROH, OF SHANESVILLE, OHIO.

THILL-COUPING.

SPECIFICATION forming part of Letters Patent No. 276,580, dated May 1, 1883.

Application filed January 30, 1883. (No model.)

To all whom it may concern:

Be it known that I, JOHN GROH, a citizen of the United States of America, residing at Shanesville, in the county of Tuscarawas and State of Ohio, have invented certain new and useful Improvements in Shaft-Shackles; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to improvements in shackles for shafts or poles in carriages, and has for its object to prevent rattling without the employment of rubber, as well as the easy and quick removal or attachment of the shafts or pole to the carriage. These objects are attained by the devices illustrated in the accompanying drawings, forming a part of this specification, in which—

Figure 1 is an elevation showing the parts applied to the axle of a carriage or buggy, and Fig. 2 a view partly in section.

The letter B represents a shaft or pole strap, of iron. H is a bolt, which passes through the end of it and enters the recess formed by the upper and lower part of the shackle when brought together, (indicated by the letters F' in Fig. 2.)

A is the upper part of the shackle, having a semicircular recess, F, and provided with threaded portions A' and A², adapted to receive the nuts a a'. It is shaped to fit snugly over the wooden and iron part of the axle-tree and bind the two together.

C is the wooden axle-tree, and D the iron part of it.

E is a heavy plate of metal, having circular perforations G G', to receive the bolts A' A², and has a part projecting upwardly provided

with a half-round recess, F', as shown in Fig. 2. The upper and the lower parts of the shackle are secured to each other by the bolts A' A² and the nuts a a'. By unscrewing the latter the two parts may be sufficiently separated without taking them entirely apart to introduce or to remove the bolt H from the recess F F', and in this manner attach or remove the shafts from the carriage. The bolt A² and the nut a are elongated in order to allow of their being partially unscrewed, so as to admit of the removal or of the insertion of the bolt H of the shaft-iron B without entirely separating the couplings from the axle C D.

It is obvious that the shackle may be adjusted and tightened to any desired extent by the nuts a a', and thus be made to fit the bolt H in such manner that all rattling and noise will be obviated.

Having described my invention, what I desire to secure by Letters Patent and to claim is—

1. In a thill-coupling, the combination of the forked shaft-iron B, having bolt H, with strap A, having semicircular recess F, elongated bolt A² and short bolt A', and plate E, having semicircular recess F' and circular openings G G', substantially as described, and for the purposes set forth.

2. In a carriage-shackle or thill-coupling, the combination of forked shaft-strap B, having bolt H, adapted to be received between semicircular openings in strap A and plate E, and elongated screw-shank A² and short shank A' with elongated nut a and short nut a', adapted to bind the whole together, as described, and for the purposes set forth.

In testimony whereof I affix my signature in presence of two witnesses.

JOHN GROH.

Witnesses:

O. C. LAWBAUGH,
E. A. LEHMER.
